UNITED STATES PATENT OFFICE

2,590,765

OPERATING ROD FOR ELECTRIC SWITCHES

Edward J. Frank, Springfield, and Cyril W. Driver Secane, Pa., assignors to General Electric Company, a corporation of New York

Application August 16, 1950, Serial No. 179,702

7 Claims. (Cl. 200—166)

1

The invention relates to the operating connections of circuit breakers, switches, or other electrical devices, particularly of the high voltage type, having a thrust rod formed of insulating material to serve the dual functions of operating a high voltage movable conducting member while effectively insulating the operating mechanism therefrom.

Operating rods for actuating switch blades and the like movable conducting parts of electrical devices must possess adequate insulating properties so that the live parts are adequately insulated from the actuating mechanism which usually is at ground potential. Furthermore, when such blades are required to move at high speed and carry heavy currents, such rods must possess high mechanical strength. Where such rods are relatively short, it is usual to arrange them so they operate in compression for withstanding their heaviest duty which, in circuit breakers, would be when closing against possible heavy short circuits. Although conventional operating rod materials, such as maple, laminated wood, and some suitable insulating compounds may have appropriate strength, they may not in themselves constitute good bearing materials for their end connections. Accordingly, it is common practice to rivet metal plates thereto at the ends so as to constitute strong metallic connectors or couplings which are well able to withstand any high bearing pressures encountered at the coupling pins. In many cases, an eyebolt or other adjustable device would be screwed into one of these metal end members or ferrules for providing longitudinal adjustment for the rods whereby to achieve proper closed contact conditions, or for adjusting the several rods in a multi-phase breaker so that they all have approximately the same loading in the closed position. Because such metal-reinforcing end members invariably extend inwardly from the coupling pins, the effective insulating length of the operating rod is thereby decreased by a corresponding amount. Thus, in many compact electrical switches, the effective insulating length of an operating rod is frequently a critical factor in deciding the space limitations of the device. Accordingly, it is desirable to attain better insulating conditions for a given operating rod without, however, increasing the effective operating length between its connecting pins.

In accordance with one aspect of our invention, we increase the virtual insulating length of the rod by extending one end (or both), beyond its coupling point and then, by means of a return coupling (or couplings), preferably of metal, con-

2

necting back to the coupling point. Such coupling means are rigidly affixed to the overextended end of the insulating rod while the return portion thereof pivotally connects, with a pin or the like, to the movable conducting member; or, if provided at the opposite end of the rod, to the actuating member thereat. In employing the rod primarily as a thrust member, the metallic return coupling may conveniently be designed as a light tensional structure.

Because such overshooting of the rod end renders it more accessible by bringing it more into the open, we, therefore, as another aspect of our invention, provide means thereat for adjusting or varying the effective rod length, such means comprising a cooperating portion of the coupling structure provided at this extended area of the rod.

Accordingly, one object of the present invention is to provide an insulating thrust rod operatively interconnecting a movable conducting member and an actuating element of the operating mechanism therefor at a different potential, which rod is elongated beyond its coupling point and then return-coupled thereto so as to enable the overall insulating length and consequently the voltage creepage length of the thrust rod to be increased without, however, increasing the actual distance between the coupling points of the movable conducting member and the actuating element of the operating mechanism.

Another object is to provide such an elongated insulating thrust rod wherein the return coupling means has incorporated therewith means for adjusting the effective rod length, and for thereafter locking the coupling means in its final adjusted position.

Other objects and advantages of the invention will appear in the following description of the accompanying drawing in which Fig. 1 is a side view of a typical high voltage circuit breaker with a part of the enclosing casing broken away in order to show an improved elongated adjustable operating rod embodying the present invention; Fig. 2 is an enlarged partial side view showing more clearly the details of construction of the improved insulating rod and its adjustable coupling arrangement shown in Fig. 1; and Fig. 3 is a cross-sectional view of the arrangement shown in Fig. 2.

Referring to Fig. 1, a high voltage power circuit breaker indicated generally by the reference character 10 is shown as of the usual removable type for metal-clad switchgear application provided with an integrally mounted operating mechanism 11 which may be in the form of a

solenoid or other suitable operating device of sufficient power to close the circuit breaker 10. The closing and opening forces exerted by the operating mechanism 11 may be transmitted to the clevis type crank 12 through any suitable form of motion converting and trip-free latching mechanism housed in compartment 13. The crank 12 is pivotally connected to an elongated insulating operating rod 14 having the adjustable coupling of the present invention for operating the conducting switch lever 15 that is pivotally mounted on a pin 16 carried by structural member 17 and supported on the high voltage insulator 18. Conventionally, the circuit breaker 10 is a polyphase device so that it will be understood that the single operating mechanism 11 may have coupled thereto a plurality of switch levers 15—usually three—only one of which is shown. The conducting switch lever or member 15 is normally at a high potential relative to operating mechanism 11 and is shown interconnected by the electric bushing conductor 19 with one of the disconnect terminals 20 of the removable circuit breaker 10, and is provided with main contacts 22 and arcing contacts 23 as well as the cooperating impulse piston means 24 that aids in effectively extinguishing the arc occurring upon the interruption of the circuit. However, the improved operating rod of the present invention may be employed with equal advantage for operating any high voltage conducting member.

As more clearly shown in the enlarged view of Figs. 2 and 3, the conducting switch lever comprising a pair of spaced blade members 15 is provided with extended portions 15' which constitute a projecting clevis, between which the lower end of the insulating operating rod 14 projects in spaced-apart relation for increasing the voltage creepage length and insulation of the rod. A thrust-transmitting return clevis coupling 26, preferably a suitably formed metallic member, has the ends thereof pivotally coupled to the ends of the switch lever extensions 15' by means of the cooperating thrust-transmitting pin 27. An enlarged and elongated slot 28 is provided centrally in the operating and insulating rod 14 for at all times clearing the pin 27 therein in spaced-apart relation with both ends and sides of the slot during actual operation as well as when making adjustment of the thrust rod 14 relative to the thrust-transmitting clevis coupling 26 so that the operating length may be varied in the manner described below.

An adjusting screw 30 projects axially from the elongated projecting end of the rod 14 so as to extend through the opening 31 formed in the center of the thrust-transmitting clevis coupling 26 with the adjustable clamping nuts 32 and 33 on opposite sides of the clevis. The adjusting screw 30 is fixedly attached to the end of rod 14 by means of the integral clevis head 35 thereof that is secured in place as by a rivet or rivets 36.

Thus, with the end of the insulating thrust rod 14 projecting in spaced-apart relation transverse the end of the conducting switch lever 15 and in central spaced-apart relation with the pivotally attached thrust-transmitting clevis or coupling 26, actual contact of the rod with the switch blade may be avoided so that creepage distance is thereby increased. Also the effective operating length of the rod 14 may be readily varied by simply turning the nuts 32 and 33 sufficiently to insure proper operating of the conducting lever 15 to a desired predetermined position after which they are securely locked

back in place. The slot 28 is made long enough to provide sufficient clearance of pin 27 therein even when making extreme adjustments to effect the proper engagement of the main contacts 22 and the arcing contacts 23 of the circuit breaker by the operating mechanism 11. Thus, the overall insulating length of the rod 14 is substantially increased, thereby correspondingly increasing the voltage creepage distance and insulation provided by the operating and insulating rod 14 without, however, requiring any increased spacing between the coupling points of the movable switch lever 15 and the actuating crank 12 of its operating mechanism 11. It will be understood that the improved elongated rod and its return clevis may be applied to either end of thrust rod 14 as desired for most convenient adjustment.

What we claim as new and desire to secure by Letters Patent of the United States is:

1. In combination, a conducting operating lever, a thrust-transmitting coupling member pivotally connected with the lever, an operating thrust rod formed of insulating material having one elongated end thereof projecting transverse the operating lever in predetermined spaced-apart relationship with the thrust-transmitting member, and means for rigidly connecting the projecting end of the rod with the thrust-transmitting member.

2. In combination, a conducting operating lever, a thrust-transmitting coupling member pivotally connected with the lever, an operating thrust rod formed of insulating material having one elongated end thereof projecting transverse the operating lever in predetermined spaced-apart relationship with the thrust-transmitting member, and means for rigidly connecting the projecting end of the rod with the thrust-transmitting member, said thrust-transmitting coupling member including lockable adjustable means for varying the effective operating length of the thrust rod.

3. In combination, a movable conducting blade member, a clevis coupling member having its ends pivotally connected with the end of the conducting blade, an operating rod formed of insulating material and having one end thereof projecting beyond the operating blade along the axis of the clevis coupling, and means including an adjusting screw for operatively connecting the projecting end of the rod with the center of the clevis coupling.

4. In combination, a movable switch member, a clevis coupling formed to cooperate with the switch member, an interconnecting pin extending through the ends of both member and coupling, an operating rod formed of insulating material and having one end thereof projecting transversely beyond the switch member along the axis of the clevis coupling and provided with a slot for clearing the pin therein and means including an adjusting screw for operatively connecting the projecting end of the rod with the center of the clevis coupling.

5. In combination, a conducting switch lever comprising a pair of blades, a clevis coupling formed to cooperate with the ends of the blades, an interconnecting pin extending through the ends of the blades and the coupling, an insulating operating rod having one end thereof projecting transversely through the blades along the axis of the clevis coupling and provided with a slot for clearing the pin therein, and means including a screw projecting axially from the end

of the rod through the center of the clevis coupling for adjustable interconnection thereof.

6. In combination, a conducting switch lever the spaced blades thereof comprising a clevis, a second clevis having the ends thereof pivotally coupled with the ends of the blade clevis, an interconnecting pin extending through the ends of both clevises, an insulating operating rod having one end thereof projecting transversely through the blade clevis along the axis of the second clevis and provided with a slot for clearing the pin therein, and an adjusting screw extending through the center of the second clevis and having clamping nuts on opposite sides thereof and provided with a clevis head for securing the projecting end of the rod therein. 15 10

7. An insulating operating rod arrangement having in combination a movable electrical conductor, the operating member formed of insulating material having one end thereof elongated so 20

as to project transversely beyond the movable conductor in spaced-apart relation therewith to increase the virtual creepage length of the insulating operating member, and a thrust-transmitting coupling member provided with means for pivotally connecting it with said movable conductor and with means for rigidly connecting it with said insulating operating member.
